W. F. Davidson

UNITED STATES PATENT OFFICE.

WILLIAM F. DAVIDSON, OF CINCINNATI, OHIO.

IMPROVED BOTTLE-FILLING MACHINE.

Specification forming part of Letters Patent No. 41,608, dated February 16, 1864.

To all whom it may concern:

Be it known that I, WM. F. DAVIDSON, of Cincinnati, Hamilton county, Ohio, have invented a new and useful Improvement in Machines for Filling Bottles; and I do hereby declare the following to be a full, clear, and exact description of the nature, construction, and operation thereof, reference being had to the accompanying drawings, making part of this specification.

My improvement relates to the class of devices employed for the rapid and accurate filling of bottles, phials, and other small vessels by the use of a syringe; and my invention relates to, first, a provision for securing a constant and uniform supply of liquor in the syringe barrel or cylinder, whether the discharge be fast or slow, and with no additional manipulation, the devices by which the discharge is effected being made also available for replenishing the cylinder; second, a provision to avoid spillage and save liquors in the intervals of charging.

The accompanying drawing is a longitudinal section of an apparatus embodying my invention.

A is a cylinder open at top and discharging by a nozzle, B, which issues from the bottom of the cylinder on the side nearest to the operator. The ventage-nozzle B is in the intervals of discharging closed automatically by a valve or stopper, C.

D is a plunger made to fit the cylinder A, its rod being hinged to a lever, E, which is retracted by means of an upward-bearing spring, F. A rod, G, depending from the lever E, and connected to a treadle, H, enables the apparatus to be worked by means of the foot of the operator.

The lever E is so connected by rods I and I' and lever J to the stopper C as to lift said valve, and thus open the ventage B in and

during the act of depressing the piston or plunger D, and to automatically close said valve the instant that the pressure of the hand or foot is withdrawn from the lever E. The rod I' for this purpose traverses the piston, in which it is made to nicely fit, or is otherwise secured against leakage by a stuffing-box or the like.

The automatic replenishment of the cylinder is secured by the following means: K is an inlet to the cylinder closed by an inwardly-opening valve, L, and communicating with a barrel, M, or other reservoir by means of a flexible pipe, N. O is an aperture in the plunger closed by a plug, P, to enable the charging of the cylinder independently of the suction-pipe N. Thus when it is desired to prime the pump the plunger may be temporarily withdrawn, and a small quantity of the liquor being poured into the cylinder, the plunger is pressed down until the liquor rises through the aperture O, which is then closed, and the suction-pipe being inserted into the barrel, the operation may proceed in the regular way.

I claim herein as new and of my invention—

1. The provision of the valve-guarded inlet K L and flexible or other suction pipe M in the described combination with a bottle-filling syringe, substantially as set forth.

2. The provision of a stopper or valve, C, at the ventage, of a bottle-filling syringe, said valve being made to close and open automatically in conjunction with the action of the piston, substantially as set forth.

In testimony of which invention I hereunto set my hand.

W. F. DAVIDSON.
